UNITED STATES PATENT OFFICE.

JOHN E. GORNEY, OF ERIE, PENNSYLVANIA.

SURGICAL CRADLE.

1,259,510.

Specification of Letters Patent. Patented Mar. 19, 1918.

Application filed January 2, 1918. Serial No. 210,007.

To all whom it may concern:

Be it known that I, JOHN E. GORNEY, a citizen of the United States, residing at Erie, in the county of Erie and State of Pennsylvania, have invented certain new and useful Improvements in Surgical Cradles, of which the following is a specification.

This invention relates to improvements in surgical devices and it is the principal object of the invention to provide a cradle for supporting fractured limbs of persons, during the knitting or mending process, in a manner such as will greatly lessen the pain here-
10 tofore caused by the forms of cradle now commonly used, wherein no movement is given to permit the easing of a limb to different positions.

It is a more specific object of the invention to provide a cradle of the character mentioned, so constructed as to permit slight movement of the limb supported therein in different directions such as may be caused when the person's body is shifted to differ-
20 ent positions, thus, preventing straining of the injured member and allowing the knitting process to be carried rapidly forward without danger of set-backs.

Other objects will be in part obvious and
30 in part pointed out hereinafter.

The invention accordingly consists in the features of construction, combinations of elements and arrangements of parts which will be exemplified in the construction here-
35 inafter set forth, and the scope of the application of which will be indicated in the following claims.

In the accompanying drawings wherein is shown one of various possible embodiments
40 of my invention:

Figure 1 is a side elevation of the im-
proved cradle, and,

Fig. 2 is an end elevation thereof show-
ing parts in section.

Having more particular reference to the drawings, in connection with which like reference characters will designate corre-
45 sponding parts throughout the several views, 1 represents the frame of the im-
proved cradle, which as will be noted com-
prises spaced end supporting members hav-
ing hollow posts 2 arranged upon the op-
posite sides thereof, the said end pieces be-
ing connected by means of longitudinally
50 disposed rods 3. Coil springs 4 are arranged
in the hollow portions of the posts 2 and

receive thereon the enlarged lower ends 5 of standards 6, which standards, as will be noted, carry bearing elements 7 upon their upper ends and are secured to the same by 60 set-screws 8 turned into engagement there-
with. Screw threaded caps having open-
ings formed in the top thereof and indi-
cated by the numeral 9 are turned into en-
gagement with complementally threaded 65 portions formed upon the upper ends of the various posts 2, thus, providing stop means for limiting the upward movement of the standards 6 with relation to their respective posts.

Curved brackets or swings 10 are pro-
vided and have off-set end portions 11
which as will be noted, are fitted into the oppositely disposed bearings 7 arranged upon the upper ends of the standards 6. In 75 this connection, it is to be noted that the sev-
eral swings will be permitted to swing lon-
gitudinally of the frame, for a purpose
which will be hereinafter apparent.

A basket designated by the numeral 12 is 80 provided and as will be noted, is formed from a plurality of interengaged wires; one end of the basket being upturned as at 13 to provide an efficient rest or stop for the foot of the injured person. Segmental brackets 85 14 are arranged over the bottom of the bas-
ket 12 and carry bifurcated bearings 15 thereon, in which rollers 16 are mounted, the said rollers having concaved peripheral surfaces adapted to be fitted over the corre-
spondingly curved surfaces of the several swings 10. By so engaging the rollers 16 90 with the several swings 10, it will be readily understood that the basket will be allowed to move transversely of the frame 1. 95

When in use, the fractured limb of a per-
son is arranged in the basket, the foot eng-
aging the upturned portion 13 and, ob-
viously, serves to prevent undue movement of the same. Since the basket is allowed lon-
gitudinal and transverse movement with re-
lation to the frame of the cradle, the person 100 may readily shift his or her position with-
out paining the injured member and also
without straining the mending or knitting
portions thereof, thus, materially facilitat-
ing the knitting process. Furthermore, by
reason of the coil springs 4, a yieldable sup-
port is afforded the injured limb, hence, al-
lowing the basket to give slightly upon the 110 shifting of a person as well as preventing
detrimental vibration of the cradle.

To permit the moving of the cradle over a floor or other surface, anti-frictional casters 17 may be and preferably are arranged upon the bottoms of the various posts 2.

5 Manifestly, the construction shown is capable of considerable modification and such modification as is within the scope of my claims I consider within the spirit of my invention.

10 I claim:—

1. A surgical cradle including spaced end pieces having curved intermediate portions and hollow posts arranged on the opposite sides thereof, spring means arranged in the 15 hollow posts, standards receivable on said spring means, and a basket supported on said standards and movable longitudinally and transversely of the frame.

2. A surgical cradle including a frame, 20 yieldably supported standards arranged adjacent the corners of said frame, and a basket supported on said standards and movable longitudinally and transversely of the frame.

25 3. A surgical cradle including a frame having a plurality of yieldably supported standards arranged thereon, swings pivotally supported between the standards, and a basket movably mounted on said swings.

4. A surgical cradle including a frame 30 having a plurality of spring mounted standards arranged thereon, curved swings pivotally supported between said standards and movable longitudinally of the frame, and a basket slidably mounted on said swings. 35

5. A surgical cradle including a frame having a plurality of resilient standards arranged thereon, and a basket having a foot rest formed adjacent one end thereof supported on said standards and movable longitudinally and transversely of the frame. 40

6. A surgical cradle including a frame, a plurality of resilient standards arranged adjacent the corners of said frame, swings pivotally supported between the standards, 45 and a basket having a foot rest formed adjacent one end thereof slidably mounted on said swings.

7. A surgical cradle including a frame, a plurality of yieldably supported standards 50 arranged adjacent the corners of said frame, and a basket having a foot rest formed adjacent one end thereof supported on said standards and movable longitudinally and transversely of the frame. 55

In testimony whereof, I affix my signature hereto.

JOHN E. GORNEY.
